Inventor
Frank Prokop,

UNITED STATES PATENT OFFICE

FRANK PROKOP, OF MILWAUKEE, WISCONSIN, ASSIGNOR OF ONE-TENTH TO MARY VANA, OF MILWAUKEE, WISCONSIN.

BIT-STOCK.

1,120,334.

Specification of Letters Patent.

Patented Dec. 8, 1914.

Application filed May 26, 1914. Serial No. 841,095.

To all whom it may concern:

Be it known that I, FRANK PROKOP, a citizen of the United States, residing at Milwaukee, in the county of Milwaukee and 5 State of Wisconsin, have invented new and useful Improvements in Bit-Stocks, of which the following is a specification.

This invention relates to screw drivers and has for its primary object to provide a 10 tool of this nature which is adapted to be used in the ordinary well known manner in driving certain kinds of screws, and particularly large ones, but which is provided with a crank device which permits use of 15 the device in driving small screws with great rapidity.

A further object of the invention is to provide a screw driver of this character which is composed of few parts and is extremely 20 simple in construction, whereby it will be efficient and reliable in operation, and may be manufactured at a small cost.

The invention consists in the features of construction, combination, and arrangement 25 of parts, hereinafter fully described and claimed, reference being had to the accompanying drawings, in which:

Figure 1 is a side elevation of the tool, showing the operating crank handle in its 30 folded position; Fig. 2 is an end elevation of the same; Fig. 3 is a longitudinal sectional view on line 3—3 of Fig. 2; Fig. 4 is a similar view showing the crank device operative; Fig. 5 is a transverse sectional view 35 on line 5—5 of Fig. 4; and, Fig. 6 is a similar view on line 6—6 of Fig. 4. Fig. 7 is a sectional view taken on line 7—7 of Fig. 4.

In the drawing, the numeral 1 designates the elongated handle of the tool, which is 40 constructed preferably of wood or like material and is provided with a longitudinal bore 2 in which a metallic bushing 3 is mounted. This bushing is provided with a longitudinal bearing opening, whose major 45 portion is cylindrical but which has one end thereof constructed non-circular in transverse section as at 4. The handle is provided exteriorly in its sides with enlarged transverse grooves 5, which afford finger-holds. A driving shaft 6 has its cylindrical 50 end portion 7 rotatably and slidably mounted within the bushing, a non-circular portion 8 being provided upon the shaft for engagement within the non-circular portion 4 of the bushing opening when the handle is

forced inwardly upon the shaft, as shown particularly in Figs. 1 to 3 inclusive. A head 9 is detachably mounted upon the end of the shaft which projects outwardly from the end of the handle bushing opposite to 60 that in which the non-circular portion 8 is adapted to fit. This end of the shaft is also non-circular in cross-section so that it fits within the correspondingly shaped opening 10 in the head 9 to prevent relative rotation of the head and shaft. A securing screw 11 is detachably mounted within this end of the shaft and a washer 12 is mounted between its head and the head 9 so as to secure the latter in position upon the 65 shaft, wherein its inner face is adapted for frictional engagement with the bearing plate 13 mounted upon the adjacent end of the handle, when the shaft is in its operative position with its non-circular portion 8 70 cut off engagement with the portion 4 of the bushing opening.

An operating crank 14 having a handle 75 15 is pivotally connected at its inner end with the head 9 by means of the tangentially disposed pivot pin 16. By means of this crank, the shaft may be rotated when in its operative position with respect to the handle. The crank, however, is adapted to be folded inwardly into inoperative position 80 within a transverse recess 17 in the outer end of the head 9, when the shaft is inoperative. The opposite end of the shaft 6 is provided with a screw-engaging portion 18. This screw driver is peculiarly adapted for 85 use by jewelers, watch makers, and piano makers, for it may be used to drive small screws, such as are found in watches, clocks, and the like, with great rapidity by operation of the crank. When it becomes necessary to use the device for driving large 90 screws, in which operation greater power is required, the shaft is moved into its inoperative position, after the handle has been turned to bring the non-circular portion 4 of its bushing opening into proper registration with the portion 8 of the shaft. The crank is then folded inwardly to its inoperative 95 position and the handle is grasped with the fingers engaging the recesses 5, whereupon 100 the screw driver may be turned in the manner in which the ordinary form of screw driver is operated.

What is claimed is:

1. A bit stock comprising a handle pro- 110

vided with an opening therein having a non-circular portion, an operating shaft rotatably and longitudinally adjustably mounted within the said opening with its ends projecting outwardly therefrom, one end of the shaft being provided with an engaging portion, the shaft being provided further with a non-circular portion adapted to engage within the non-circular portion of the handle opening in inoperative position, a head fixedly mounted upon the opposite end of the shaft and being adapted to be disposed in spaced relation to the adjacent end of the handle when the shaft is in inoperative position with respect to the handle, and means by which the head may be operated.

2. A bit stock comprising a handle provided with an opening therein having a non-circular portion, an operating shaft rotatably and longitudinally adjustably mounted within the said opening with its ends projecting outwardly therefrom, one end of the shaft being provided with an engaging portion, the shaft being provided further with a non-circular portion adapted to engage within the non-circular portion of the handle opening in inoperative position, a head fixedly mounted upon the opposite end of the shaft and being adapted to be disposed in spaced relation to the adjacent end of the handle when the shaft is in inoperative position with respect to the handle, the said head being provided in its outer end face with a transverse recess, and a foldable operating crank having one end pivotally connected with the head in one end of its recess and being adapted to be folded within the recess in inoperative position.

tion with respect to the handle, and an operating crank provided upon the said head.

3. A bit stock comprising a handle provided with an opening therein having a non-circular portion, an operating shaft rotatably and longitudinally adjustably mounted within the said opening with its ends projecting outwardly therefrom, one end of the shaft being provided with an engaging portion, the shaft being provided further with a non-circular portion adapted to engage within the non-circular portion of the handle opening in inoperative position, a head fixedly mounted upon the opposite end of the shaft and being adapted to be disposed in spaced relation to the adjacent end of the handle when the shaft is in inoperative position with respect to the handle, the said head being provided in its outer end face with a transverse recess, and a foldable operating crank having one end pivotally connected with the head in one end of its recess and being adapted to be folded within the recess in inoperative position.

In testimony whereof I affix my signature in presence of two witnesses.

FRANK PROKOP.
